N. SORENSEN

WASHBOARD

Filed Nov. 9, 1921

Inventor
Nels Sorensen
By Frank E. Liverance, Jr.
Attorney

UNITED STATES PATENT OFFICE.

NELS SORENSEN, OF TRAVERSE CITY, MICHIGAN.

WASHBOARD.

Application filed November 9, 1921. Serial No. 513,872.

To all whom it may concern:

Be it known that I, NELS SORENSEN, a citizen of the United States of America, residing at Traverse City, in the county of Grand Traverse and State of Michigan, have invented certain new and useful Improvements in Washboards; and I do hereby declare the following to be a full, clear, and exact description of the invention, such as will enable others skilled in the art to which it appertains to make and use the same.

This invention relates to wash boards. It is a primary object and purpose of the present invention to make a wash board in which the rubbing plate thereof may be interchanged or replaced at will, as when such plate becomes worn out or perforated so as to be useless for washing purposes, or when the character of the rubbing plate should be different for different kinds of materials washed thereon. A further object of the invention is to make a wash board at low cost of manufacture whereby it may be marketed at low cost, and one in which the frame part may be used until it is worn out without the necessity of throwing the entire board away when the rubbing plate becomes worn out and useless. A still further object of the invention is to construct the wash board so that there are no projecting parts on which the one using it may be injured, the board having smooth and rounded surfaces without sharp corners or jagged projections liable to produce injuries on use thereof. These and many other objects and purposes, together with constructions for effecting the same will appear as understanding of the invention is had from the following description, taken in connection with the accompanying drawings, showing several modifications of the invention, in which drawings,

Fig. 1 is a perspective view of a preferred form of wash board construction, showing the same in position for the interchanging or replacement of rubbing plates therefor.

Fig. 2 is a perspective view showing the wash board in position for use.

Fig. 3 is a longitudinal vertical section, with parts broken away of the wash board of the first form, the section being taken on the line 3-3 of Fig. 2.

Fig. 4 is a transverse section on line 4-4 of Fig. 2.

Like reference characters refer to like parts in the different figures of the drawings.

In the construction of wash board shown in Figs. 1, 2, 3 and 4, two side bars 1 and 2 are used, being spaced a distance apart and held in spaced relation to each other by back cross boards 3 and 3^a nailed or otherwise permanently secured to the bars, board 3 being at the upper ends of the bars and board 3^a nearer the lower ends thereof, but some distance above such lower ends. A top guard board 4 is secured over the upper ends of the side bars, lying between the same and projecting a short distance forward, as is common in wash boards.

A back board 5 is located between and permanently secured to the side bars 1 and 2, being located below and a short distance in front of the upper board 3. At its upper and lower edges cross bars 6 are located, being positioned between the side bars 1 and 2 and permanently secured at their ends thereto. The upper bar 6 has a downturned lip 7 and the lower bar a similar upturned lip 7 so that the back 5 and said bars 6 with lips 7 serve as a container or receiver for the rubbing plates, as will be later described. On the inner side of bar 1 a groove or recess 8 is cut, into which one side edge of back board 5 extends, the groove being wider than the thickness of board 5.

The side bar 2 is of less width than bar 1 so that the ends of the guides made by lips 7 over board 5 are open at the ends adjacent said bar 2. To close such open ends a third bar 9 is laid over the upper side of bar 2, it being provided on its inner side at its under portion with an elongated recess 10 of substantially square cross section of a length substantially equal to the length of groove 8. One of the side bars is split longitudinally in the plane of the front face of the back to form front and rear sections. This bar 9 is pivotally connected to the bar 2 under it, a screw 11 passing through the same at a point below the lower cross bar 6 and into the lower bar 2.

It is designed that a plurality of rubbing plates, made of metal shall be placed over the back board 5, the upper edges being guided between bars 6 and retained in place by lips 7, and the side edges of the plates coming to bar 1 entering the groove 8. I have shown two rubbing plates 12 and 12^a, placed one over the other, one being formed with wider spaced and deeper corrugations than the other. Any number of the plates may be used and the invention is not limited

to the use of two of the plates. After being put in place, the retaining bar 9 is swung about its pivot screw 11 so as to lie directly over the bar 2 and is held in place by a bolt 13 passing through bar 9 and through an opening 14 in bar 2 and board 3, its end being threaded for the attachment of a thumb nut 15 which may be screwed as tightly as needed against the under side of bar 2. In such position, the opposite side edges of the rubbing plates are located within the recess 10 in bar 9, the ends of the guides for the plates are closed, and the combined widths of the bars 2 and 9 being the same as that of bar 1, a symmetrical construction is made.

It is obvious that the rubbing plates 12 and 12^a can be easily removed and interchanged so as to bring either one desired uppermost for use. For the coarser and heavier materials washed, the plate 12 is better, and for finer materials the plate 12^a. By merely taking off the thumb nut 15 and withdrawing bolt 13 from opening 14, the retaining bar 9 may be swung around, as shown in Fig. 1 so that the rubbing plates may be removed and interchanged or replaced when worn out.

With my invention, not only may a substantial and durable construction of wash board be made economically, but the provision in the construction by means of which the rubbing plates may be interchanged for different classes of goods washed is one of value in that one wash board only is needed instead of a number thereof, and the rubbing plates not used are contained in the wash board and protected from bending or other injury, such as would be liable to occur if the rubbing plates not used were separated from the wash board. Furthermore, the rubbing plates are the parts subjected to the hardest service and usually become worn out or perforated so as to be useless long before the frame of the wash board is ready to be discarded, and with my invention new rubbing plates may be substituted for those worn out and the wash board made practically as good as new at slight expense. This is a feature of economy which makes my invention of value. Every part of the completed wash board is smooth and one using the same is not liable to injury. This is particularly true of the rubbing plates, which if ever ruptured or otherwise injured

so as to leave jagged projecting parts, are immediately discarded and new ones put in place.

The invention is defined in the appended claims and I consider myself entitled to all forms of structure coming within the scope thereof.

I claim:

1. A wash board comprising spaced apart side bars a fixed back rigidly connecting the side bars, upper and lower transverse guide bars rigid with the side bars and located at the upper and lower edges of the back and provided thereat with guide flanges, a rubbing plate supported against the said back and having its upper and lower edges fitted in the guide grooves formed between said back and said flanges, one of the said side bars being split longitudinally in substantially the plane of the front face of the back to form front and rear sections, the front section being pivoted to the rear section of the side bar below the lower guide bar and adapted to swing outwardly to expose the guide grooves at one side of the wash board to permit the removal of the rubbing plate and means for rigidly securing the front section upon the rear section of the said split side bar.

2. A wash board comprising spaced apart side bars provided in their inner faces with longitudinal recesses, a fixed back rigidly connecting the side bars with its side edges in said recesses, upper and lower transverse guide bars rigid with the side bars and located at the upper and lower edges of the back and provided thereat with guide flanges, a rubbing plate supported against the said back and having its upper and lower edges fitted in the guide grooves formed between said flanges and said back, said rubbing plate having its side edges arranged in the said recesses, one of the side bars being split longitudinally in approximately the plane of the front face of the back to form front and rear sections, the front section being pivoted to the rear section below the lower transverse bar and adapted to swing outward to expose the guide grooves at one side of the wash board to permit the removal of the rubbing plate, and means for rigidly securing the front section of the split side bar to the rear section thereof.

In testimony whereof I affix my signature.
NELS SORENSEN.
